(57) **CLAIM**

I claim the ornamental design for a cable eyelet, as shown and described.

DESCRIPTION

FIG. 1 is a perspective view of a cable eyelet;
FIG. 2 is a left side elevation view thereof;
FIG. 3 is a right side elevation view thereof;
FIG. 4 is a front side elevation view thereof;
FIG. 5 is a rear side elevation view thereof;
FIG. 6 is a bottom plan view thereof; and,
FIG. 7 is a top plan view thereof.
The broken line showing of the rod is for the purpose of illustrating an environment of use of the cable eyelet.
